INTERMITTENT STROKE CONTROL FOR
RAM-FEED STOKERS

Walter J. Haag, Dayton, Ohio, assignor to The
Brownell Company, Dayton, Ohio, a corpora-
tion of Ohio

Application July 14, 1939, Serial No. 284,564

12 Claims. (Cl. 193—226)

The present invention appertains to stokers of the ram-feed type wherein coal is fed to the furnace or retort thereof by the reciprocating movement of a ram acting upon fuel deposited in front of said ram by gravity from the usual hopper. More particularly, the invention relates to means for controlling the stroke of the ram whereby to enable pre-determination of the number of strokes thereof in a given period and to facilitate any desired variation in such pre-determination of the number of strokes of said ram for a particular period.

Stokers of the type described ordinarily comprise a ram reciprocable within a casing positioned adjacent a suitable opening in the furnace wall into which fuel is desired to be fed, and means operated from a suitable source of power for reciprocating the ram, comprising a pitman pivotally associated with the ram and connected with a crank operated by the source of power. The means heretofore proposed for varying the amount of coal fed to the furnace during a given period have involved either a variation in the speed of reciprocation of the ram, or variation in the length of effective stroke thereof. Both of these means for accomplishing the purpose desired have been subject to disadvantages.

Varying the speed of reciprocation usually involves variation of the speed of the motor employed as a source of power for reciprocating the ram. The same motor is ordinarily utilized to operate the fan or other means for providing forced air draft. Variation in the speed of the common source of power will, under such condition, increase or decrease the forced air draft in a manner disproportionate to the draft requirement based on the proportionate increase or decrease in amount of fuel fed during a given period resulting from the variation in the speed of reciprocation of the ram.

Means for varying the effective length of stroke of the ram ordinarily comprises provision for adjusting the degree of lost motion of the pitman. This is accomplished by providing an adjustable screw bearing against the cross head associated with the crank. Adjustment of the screw is ordinarily made by guesswork as no provision is ordinarily made for gaging such adjustment. Varying the length of the stroke involves disadvantage in operation arising from the fact that when the stroke is shortened so that the ram does not make the full stroke, insufficient agitation of the fuel bed results. Constant agitation of the fuel bed is extremely important to prevent caking of the fuel, to produce better

combustion, and to enable a wider range of fuels to be employed. Shortening the ram stroke reduces the extent of agitation and prevents proper distribution of fuel throughout the length of the retort, resulting in an unbalanced fuel condition and reducing the efficiency of the furnace.

Moreover, since the effective opening of the throat of the hopper is limited by shortening of the ram stroke, arching of the fuel in the hopper may occur because of the inability of said fuel to pass readily through the limited opening.

The present invention overcomes all these difficulties inherent in previous constructions providing for variation in the amount of fuel fed during a given period.

In carrying out my invention, I provide means for varying the amount of fuel fed to the furnace during a given period, comprising provision for disconnecting the ram from operative relation with the crank when the ram is at the end of its full stroke closing the bottom hopper opening. I further provide timing mechanism for controlling the number of times the ram is caused to be disconnected from the crank during a given period, and, consequently, the number of strokes of said ram during said period. This mechanism comprises a timing gear driven from the crank shaft and having associated therewith instrumentalities for causing periodic disconnection of the ram from the crank through the actuation of a device adapted to be positioned for engagement with a portion of the pitman connecting the ram and crank, which device is operated by the energizing and de-energizing of a solenoid controlled by the rotation of the timing gear.

It is an important object of the invention to provide means for producing a pre-determined number of strokes of the ram during a given period and for enabling said pre-determined number of strokes to occur at substantially equal intervals throughout said period.

Another object of the invention is to provide means for pre-determining the number of strokes of the ram which shall occur during a given period.

In carrying out these objects, the timing gear is provided with vanes extending from its periphery, designed to coact with trip mechanism, the position of which may be readily varied respecting the timing gear. The timing gear is so designed as to enable a pre-determined number of the vanes to coact with the trip mechanism during a full revolution of said gear, depending upon the relative position of the trip mechanism respecting the vanes.

Another object of the invention is to provide trip mechanism for coaction with the vanes of the timing gear, comprising novel means for preventing injury to either the timing gear or trip mechanism resulting from varying the position of the latter during rotation of said gear.

Another object of the invention is the provision of quick-acting switch means for energizing the solenoid upon actuation of the trip mechanism.

Other objects, advantages and features of novelty will appear more fully as the description of the invention progresses in conjunction with the accompanying drawings in which:

Figure 1 is a top plan view of stoker mechanism embodying the improvements of the present invention.

Figure 2 is a longitudinal vertical section on the line 2—2 of Figure 1, looking in the direction of the arrows.

Figure 3 is an end view, partly in section, said section taken on the line 3—3 of Figure 1.

Figure 4 is a perspective view, partly in section, of a portion of the device showing more particularly the disconnect instrumentalities.

Figure 5 is a side view of the timing mechanism and control means therefor, parts of the same being shown in section.

Figure 6 is a horizontal sectional view taken on the line 6—6 of Figure 5, looking in the direction of the arrows.

Figure 7 is a transverse vertical sectional view of the instrumentalities shown in Figure 5.

Figure 8 is an end view of the control instrumentalities.

Figure 9 is a wiring diagram showing the relation of the source of power, switch means and solenoid.

Figure 10 is a side view of one of the frame members for journaling the crank shaft, showing more particularly the disconnect mechanism.

Now, describing the invention in detail, and referring more particularly to Figures 1 and 2, the numeral 1 designates a ram case having an opening 2 registering with the fuel-receiving opening 3 of a furnace not shown. The ram case 1 is provided with a throat portion 4 over which is adapted to be positioned a fuel hopper 4a. Reciprocably mounted in the ram case 1 is a ram or fuel feed plunger 5 having associated therewith an auxiliary ram 6. A pitman 7 formed with a bearing 7a is pivotally connected to the ram 5 by means of a cross pin 8, extending through said bearing 7a and journaled in suitable bearings provided in said ram.

At its opposite end the pitman is provided with flanges 7b and 7c having openings 7d and 7e through which extend the reduced ends 9a and 10a of guide rods 9 and 10 respectively, said guide rods being secured to the pitman 7 by suitable nuts 11 and 12. A bridge block 13 is secured to the opposite ends of said guide rods 9 and 10. A slide block 14 formed of cooperating sections 14a and 14b provides a bearing for the crank 15a of a crank shaft 15 journaled in side frame members 80 and 81. The sections 14a and 14b are provided with registering openings 14c and 14d through which extends the guide rod 9, and registering openings 14e and 14f through which extends the guide rod 10, the sections of the slide block being held together by fastening means 16 and 17, and said block being slidably bodily along said rods 9 and 10.

The section 14a of the block 14 is formed with a latch member 18 extending longitudinally

through an opening 7f in the pitman 7 into a longitudinally slotted portion 7g of said pitman. Positioned within the slot 7g is a latch member 19 pivoted to the pitman 7 by the cross pin 7x. 5 A cross member 7y extends across the slot 7g between the sides of the pitman 7.

When the latch members 18 and 19 are in coupled relation, the pitman 7 is connected to move with the slide block, thereby causing the ram 5 to 10 be reciprocated by rotation of the crank 15. When the latch 19 is disengaged from the latch 18, by means to be hereinafter described, the ram 5 will be uncoupled from crank 15a and rotation of the crank shaft 15 will cause the slide block 14 to move freely on the guide rods 9 and 10 without actuation of the ram 5.

As seen best in Figures 3 and 4, the latch 19 is formed with a hook portion 19a extending to one side of the pitman 7 and bridging the portion 7h of said pitman forming one of the sides of the slot 7g.

Means, hereinafter called the disconnect mechanism, is provided for cooperation with one of the latches to disconnect the same, thereby to 25 uncouple the ram from the crank. Said means generally comprises a member projected into the path of the hook 19a by the energizing of a solenoid. The details of construction and operation of this disconnect mechanism will now be described.

Secured to the outer side of the frame member 80 is a bracket 20 having bearing members 20a and 20b extending through a suitable opening 80a in said bracket. Journaled in said bearing members is a stub shaft 21 carrying a rocker arm 22. Secured to the bracket 20 is a solenoid 23.

One end of a connecting rod 24 is pivotally secured to the rocker arm 22, at 25, and the other end of said connecting rod is pivotally secured to the core of the solenoid, at 26. The rocker arm 22 is formed with a bearing portion 22a in which is journaled a roller shaft 27 carrying a roller 28.

When the solenoid 23 is energized, the connecting rod 24 is moved upwardly actuating the 45 rocker arm 22 to project the roller 28 beneath the overhanging portion of the hook 19a, when the pitman 7 is at a point in its vertical oscillatory movement such that the depending portion 19b of the hook 19a is above the roller 28. As the pitman moves downwardly in its oscillatory movement, the depending portion 19b of the hook 19a engages the roller 28. The portion 19b of the hook 19a is formed with an undercut flanged portion 19c engaging the inner edge of the roller 28 to prevent the same from being retracted out of engagement with said hook when the solenoid 23 is de-energized.

The depending portion 19b of the hook 19 is tapered as at 19d, above the flange 19c, so as to 60 prevent the roller 28 from becoming hooked above said flange in the event the rocker arm 22 should be projected toward the pitman when said flange 19c was below the roller 28. This would not happen in normal operation of the device but might occur if the crank shaft 15 were accidentally caused to rotate in a direction opposite that indicated by the arrow in Figure 2.

When the solenoid is energized so as to project the rocker arm 22, and consequently the roller 23 into the path of the hook 19a during the downward oscillatory movement of the pitman 7, engagement of the roller 28 with the hook 19a prevents the latch 19 from continuing to move downwardly with the pitman 7 as the latter progresses toward the center of its vertical oscil-

latory movement at which time the ram will have reached the limit of its inward reciprocatory movement. The engagement of the hook 19a with the roller 28 will thus cause the latch 18 to be disengaged from the latch 16 as the downward oscillatory movement of the pitman continues thereafter.

After disconnection of the latches 18 and 19, the slide block 14 will continue to engage the flanges 7b and 7c of the pitman 7, until the latter reaches the center of its vertical oscillatory movement at which time the ram 5 will have reached the limit of its inward reciprocatory movement. As the crank shaft 15 continues its rotation thereafter, the slide block 14 will move freely on the guide rods 9 and 10, the pitman continuing its oscillatory movement without reciprocatory effect upon the ram 5. The hook 19a and roller 28 will continue to be engaged during the rotation of the crank until such time as the pitman 7 reaches a point in its upward oscillatory progress high enough to withdraw the hook 19a vertically away from the roller 28.

Upon disengagement of the hook 19a from roller 28, the latter will be restored to its normal retracted position by movement of the rocker arm 22 resulting from the over-balancing effect of the portion 22b thereof connected to the solenoid 23, the latter having meanwhile been de-energized. Means generally indicated at 29 for actuating the disconnect mechanism comprises timing means, trip instrumentalities and control means therefor. The details of construction and operation of this disconnect actuating means will now be described.

As seen best in Figure 1, the crank shaft 15 is provided at one end with a pinion 30 meshing with a timing gear 31. Referring now more particularly to Figures 5 to 9, the timing gear 31 is seen to be journaled on a stub shaft 32 secured to a housing 33 attached in any convenient manner to the bearing 81 supporting one end of the crank shaft 15. The timing gear 31 is provided with a plurality of vanes 34a, 34b, 34c, 34d, 34e, 34f, 34g and 34h extending from the periphery of the timing gear. These vanes are of graduated axial lengths for a purpose to be hereinafter pointed out.

The ratio of the timing gear 31 to the pinion 30 is dependent upon the number of vanes provided on the periphery of the timing gear. Since the vanes actuate the disconnect mechanism for disengaging the ram from the crank, and since, as above mentioned, it is desirable to actuate the disconnect mechanism when the pitman 7 is in a certain stage of its vertical oscillatory movement, the disconnect mechanism is preferably actuated only once during the rotation of the crank 15. The vanes 34 are, therefore, arranged on the periphery of the timing gear 31 in spaced relation equidistant from each other, the distance between said vanes being the length of the arc of rotation of the timing gear 31 during a corresponding full revolution of the pinion 30. In the embodiment of the invention shown, the ratio of the pinion 30 to the timing gear 31 is one to eight, and, consequently, eight equidistantly spaced vanes are provided on said gear. Hence, if the trip mechanism is positioned for engagement with all of the vanes 34a, 34b, 34c, 34d, 34e, 34f, 34g and 34h of the timing gear 31 during a complete revolution of the latter, the ram will be uncoupled from the crank once during each revolution of the latter. In other words, there will be eight consecutive actuations of the disconnect

mechanism during a full revolution of the timing gear 31. Thus, so long as the trip instrumentalities are positioned relative to the timing gear, as just above mentioned, the crank 15a will be continuously disconnected from the ram 5.

As mentioned above, the vanes 34 are of different axial lengths and the trip instrumentalities are movable axially respecting the timing gear 31. The trip instrumentalities may, therefore, be positioned axially respecting the timing gear in such a manner as to engage any desired number of the vanes 34 from none to eight.

The timing gear 31 is positioned on the shaft 32 by a suitable lock nut 35 and washer 36. Pivotaly mounted on an extension 32a of the shaft 32 is a balance bar 37 which is axially positioned respecting the said shaft by the shoulder 32b bearing against one edge of said bar 37 and a sleeve 38 bearing against the opposite edge of said bar. A mercury switch 39, secured between the clamping portions 40 of a bracket 41, is rockably mounted upon the shaft 32a, the bracket 41 comprising depending legs 41a and 41b journaled upon the sleeve 38 and the shoulder portion 32b.

A rock shaft 42 is pivotally connected to the balance bar 37, as at 42a, and secured to the rock shaft 42 is a link 43 pivoted, as at 44, to a crank 45a of a crank shaft 45, journaled in bearings 33a and 33b of the casing 33. Mounted for sliding movement along the crank shaft 45 is a forked trip member 46 which is adapted to be oscillated upon a corresponding movement of the crank shaft 45. For this purpose the crank shaft 45 is preferably rectangular in cross section, except at its ends which are rotatably journaled in the casing, and the trip member 46 is provided with a corresponding rectangular opening 46a for cooperation with said shaft. The trip member 46 comprises a pivoted trigger portion 46b pivoted to the trip member, as at 46c, and comprising a lever extension 46d to which is secured one end of a spring 47, the other end of said spring being secured to the trip member 46, as at 48.

The trigger 46b is thus normally positioned, as shown by the solid lines in Figure 7, with the lever extension 46d in abutment with the hub portion 46e of said trip member. A lever 49 for moving the trip member 46 axially respecting the crank shaft 45 is journaled upon the inner end of a stud shaft 50, secured to the casing 33, and comprises a rod 51 extending between the bifurcations 46f and 46g of the trip member 46.

Formed integral with the base or hub portion 49a of the lever 49 is a gear segment 49b meshing with a pinion 52a fixed to the inner end of a lever 52 journaled in the housing 33. The diameter of the pinion 52a is proportionately less than the diameter of the gear segment 49b so that a given arc of movement of the lever 52 will induce a proportionately smaller arc of movement of the lever 49, the ratio of the pinion 52a to gear segment 49b, being in the present instance one to three.

The handle portion 52b of the lever 52 is provided with a plunger 52c normally pressed inwardly toward the casing 33 by a spring 52d bearing against the enlarged end 52e of said plunger. A handle 52f is provided for withdrawing the plunger against the compression of the spring. The pointed inner end 52g of the plunger is adapted to engage one or the other of a plurality of recesses 53 in the casing 33, designated by corresponding number indicia 54 on said casing, as shown in Figure 8. The number indicia

54, related to respective recesses 53, indicate corresponding positions of the levers 52 and 49 such that when the pointed end 52g of the plunger 52 is engaged in a particular one of said recesses 53, the trip member 46 will be positioned for engagement with a given number of the vanes 34, determining the rate of fuel feed at such time. The particular number indicia 54 corresponding with the recess 53 engaged by the plunger will indicate the number of times the ram 5 will be coupled to the crank 15a during a complete revolution of the timing gear 31. For example, we will say that the lever 52 is positioned, as shown in Figure 8, with the pointed end 52g of the plunger 52 engaged in the recess 53, indicated by the numeral 4 of the number indicia 54. Under such condition the trip member 46 will be so positioned axially respecting the crank shaft 45 as to permit four of the vanes, namely 34h, 34g, 34f and 34e, to engage the trigger 46b during a complete revolution of the timing gear 31. Hence, the ram 5 and crank 15a will be uncoupled four times during each revolution of the timing gear 31, and consequently coupled four times during each revolution of said gear. Ram 5 will, of course, only be reciprocated during the revolutions of the crank in which uncoupling does not take place.

As above mentioned, the vanes 34 are of graduated axial lengths ranging from the length of vane 34a, which is the shortest, to that of vane 34h, which is the longest. Each of the other vanes is of a different length intermediate the lengths of the vanes 34a and 34h. Said vanes range in order of their length from shortest to longest in the following order: 34a, 34b, 34c, 34d, 34e, 34f, 34g and 34h. Upon reference to Figure 5, it will be noticed that this order of the range of the length of said vanes does not, however, follow the order of their proximity to one another. For example, vane 34b, which is next in length to 34a, is diametrically opposite the latter. Vane 34c, which is next in length to 34b, is not immediately proximate, vane 34e intervening. Vane 34d, which is next in length to vane 34c, is again diametrically opposite the latter. Vane 34e, which is next in length to vane 34d, is substantially opposite the latter, while vane 34f is again diametrically opposite 34e, and vanes 34g and 34h, the former being the next in length to the latter, which is the longest, are also diametrically opposite.

The reason for the arrangement of the vanes, as just described, is to space the respective disconnections of the ram from the crank as nearly as possible at equal intervals throughout the period, during a certain proportion of which it is desired to have the ram remain idle.

The range of the possible variations of the proportions of idle time to active time of the ram in the embodiment of the invention disclosed in the drawings is determined by the number of vanes with which the timing gear is provided. In the present instance, the timing gear is provided with eight vanes so that it is possible to secure a variation from zero to eight in the proportions of idle time of the ram to active time of the ram, between a condition in which the ram is active continuously during a given period and a condition in which the ram is inactive or idle continuously during a given period.

Now, if, for example, it is desired to produce a rate of feed which is three-eighths of full capacity, it will be necessary to permit the ram to be coupled with the crank during only three out

of eight revolutions of the crank. In other words the ram will be caused to be disconnected from the crank five times out of every eight revolutions of the crank. Obviously, it is desirable to provide that the revolutions of the crank which are to be effective for actuation of the ram will come at substantially equally spaced intervals during the period of eight revolutions of the crank. The arrangement of the vanes on the timing gear is such, therefore, that when the mechanism is set so as to permit only three revolutions of the crank out of eight to be effective for actuation of the ram, the trip mechanism will be adjusted so as to engage five of the eight vanes of the timing gear, and the vanes so engaged will be spaced at substantially equal intervals on the periphery of the timing gear.

Thus, when the lever 52 is positioned so that the pointed end 52g of the plunger 52b is engaged in the recess 53, designated by the numeral 3 of the number indicia 54, this indicates that the device is set for a rate of feed which is three-eighths of full capacity and the trip member 46 will be positioned axially respecting the crank shaft 45 so that the trigger 46b will engage the five vanes of the greatest axial length. The vanes engaged, therefore, will be 34h, 34g, 34f, 34e and 34d, which, while not spaced at identically equal intervals on the periphery of the timing gear 31, are nevertheless spaced at intervals as nearly as possible spread out on the periphery of said timing gear in view of the fact that all positions of adjustment of the trip member also make desirable as nearly as possible equal spacing of the vanes to be engaged during a revolution of the timing gear.

The mercury switch 39 comprises the usual glass tube 39a containing mercury 39b from which tube terminals 54a and 55 lead respectively to the solenoid 23 and the power lines 56 to which are inter-connected the motor 57 for driving the crank shaft 15, the starter 58 for said motor, and the limit control switch 59 for said starter.

When the trip member 46 is in such a position axially respecting the rock shaft 45 as to permit engagement of one or more of the vanes 34a, 34b, 34c, 34d, 34e, 34f, 34g or 34h with the trigger 46b, each engagement of one of said vanes with said trigger will cause the trip member 46 to be moved in the direction of the dotted line position thereof, shown in Figure 5, resulting in corresponding rocking movement of the crank shaft 45 and crank 45a acting to draw upwardly the link 43 and consequently the balance bar 37, which, under such condition, engages the bracket 41 to cause the same to be rocked in a counterclockwise direction respecting the shaft 32a causing the mercury 39b to flow in a leftward direction in the tube 39a, respecting Figure 5, so that the mercury completes a circuit through the terminals 54a and 55, as indicated in Figure 9. Completion of this circuit energizes the solenoid 23.

Operation

In the event it is desired to permit continuous reciprocation of the ram 5 to operate same at full capacity, for a certain period, the control mechanism will be adjusted so that the crank 15 and ram 5 will be continuously connected through the pitman 7 during such period. For this purpose, the control lever 52 will be shifted to the position indicated by the numeral "8" of the number indicia 54. The trip member 46 will

then be positioned axially respecting the rock shaft 45, as shown by the dotted line position in Figure 7, and it will be readily seen that under such condition the timing gear will rotate without engagement of any vanes 34 with the trigger 46b. Ram 5 and crank 15a will therefore be continuously coupled, i. e. eight times out of every eight revolutions of the crank.

Now, we will assume that it is desired to maintain the ram 5 idle or inactive for one-eighth of a given period, or, in other words, to operate at seven-eighths of full capacity. To this end the control mechanism will be adjusted so as to cause uncoupling of the ram 5 from the crank 15a during one out of each eight revolutions of the crank shaft 15. To accomplish such result the control lever 52 will be positioned opposite the numeral "7" of the number indicia 54. Such adjustment of the control lever 52 will position the trip member 46 for engagement with one only of the vanes on the periphery of the timing gear 31 during a complete revolution of said timing gear. The vane so engaged will be the one of greatest axial length, which is 34h.

With the control lever 52 set, as just indicated, the trip member 46 will be engaged by the vane 34h once during each eight revolutions of the crank shaft 15. At the time of each engagement, the mercury switch 39 will be rocked so as to cause the mercury 39b to complete the circuit through the terminals 54 and 55, thus actuating the solenoid 23. This will cause the rocker arm 22 to assume the full line position, indicated in Figure 3, projecting the roller 28 into the path of the depending portion 19b of the hook 19a. As before mentioned, the timing gear 31 is so calibrated respecting the pinion 30 on the crank shaft 15 that the solenoid 23 will be energized at a time when the crank 15a has raised the pitman 7 to a height such that the flange 19c is above the plane of the roller 28.

The solenoid 23 will be energized a sufficient length of time to maintain the rocker arm 22 projected to full line position, shown in Figure 3, until further revolution of the crank shaft 15 has resulted in lowering the pitman 7 so as to permit engagement of the flange 19c with the roller 28. The solenoid 23 may be de-energized at any time after such engagement because the flange 19c, contacting the inner edge of the roller 28, will maintain engagement of the hook portion 19a with said roller until the further rotation of the crank shaft 15 has resulted in raising the pitman 7 to a height sufficient to permit disengagement of the hook 19a from the roller 28.

After the hook 19a becomes engaged with the roller 28, further rotation of the crank shaft, moving the pitman downwardly, will result in uncoupling the latches 18 and 19, because the latch 19 is prevented from moving downwardly in coupled relation with the latch 18.

The inward stroke of the ram 5 will not have been completed at the time of uncoupling of the latches 18 and 19, but the ram 5 will continue to be moved inwardly by the further rotation of the crank 15 as a result of the continued engagement of the slide block 14 with the flanges 17b and 17c of the pitman 7. When the ram has reached the limit of its inward stroke, however, the further rotation of the crank shaft 15 will be ineffective to actuate the pitman 7 due to the uncoupling of the latches 18 and 19, and the crank 15a will, therefore, cause the slide block 14 to slide freely on the guide rods 9 and 10.

When the crank 15a, during the further rotation of the crank shaft 15, raises the pitman 7 to a point high enough to release the hook 19a from the roller 28, after engagement of the portion 7h of said pitman with the hook portion 19a of latch 19, the rocker arm 22 will return to the dotted line position shown in Figure 3 due to the over-balancing effect of the portion 22b of said rocker arm. Thereupon, the hook portion 19a will rest on the portion 7h of the pitman 7 until further rotation of crank 15a lowers pitman 7 sufficiently to permit engagement and subsequent coupling of latches 18 and 19 when the crank 15a returns the slide block 14 to a position of abutment with the flanges 17b and 17c during the downward movement of the pitman 7. Thereupon, coupled relation of ram 5 and crank 15a being re-established, further rotation of the crank shaft 15 will result in continued normal reciprocation of the ram 5 until the latches 18 and 19 are again uncoupled upon actuation of the disconnect means resulting from engagement of the trip member 46 with one of the vanes on the timing gear 31. With the control lever 52 set at the number "7" position, the ram and crank will be uncoupled, of course, during one revolution only out of every eight revolutions of the crank.

Adjustment of the control lever 52 to a position corresponding with one of the numerals 54 will result in positioning the trip member 46 so as to engage a particular number of vanes of the timing gear 31, conditioning the timing mechanism for initiating uncoupling of the latches 18 and 19 a number of times during every eight revolutions of crank 15a corresponding to the particular numeral of the number indicia 54 opposite which said lever 52 is positioned. It will be readily seen, of course, that when the control lever 52 is positioned opposite the numeral "0" of the number indicia 54, the trip member 46 will be engaged by each of the vanes 34a, 34b, 34c, 34d, 34e, 34f, 34g and 34h, resulting in uncoupling the latches 18 and 19 during each revolution of the crank shaft 15 and thus maintaining the ram 5 continuously at the limit of its inward stroke.

It will be noticed that the relation of the trigger 46d to the trip member 46 is such that the latter may be shifted axially respecting the crank shaft 45 regardless of the position of rotation of the timing gear 31. Should the trip member 46 happen to be moved rightwardly, referring to Figure 7, from the dotted line position, indicated in Figure 7, at a time when such axial shifting of the trip member would cause the trigger 46b to engage the outer edge of one of the vanes on the timing gear 31, the trigger 46b would simply be caused to move about its pivot 46d to the angular dotted line position of Figure 7, during such axial shifting of the trip member 46, without injury thereto.

Further rotation of the timing gear 31, moving the vane so engaged out of contact with the trigger 46b, will result in restoration of the vertical position of the trigger 46b by action of the spring 47.

Upon reference to Figures 5 and 7 it will be noticed that the bracket 41 is spaced somewhat from the upper edge of the balance bar 37 resulting in a certain amount of play between the bracket and said bar. This provision has the following result. The flow of mercury 39b in the tube 39 lags somewhat behind the speed of flow which would normally result from the an-

gular movement of the bar 31 if the bracket and bar were integral. At the moment the mercury overbalances the bracket 41 in the direction of the terminals 54 and 55, however, said bracket moves with greater rapidity toward the limit of its overbalanced position in that direction, as defined by the abutment of said bracket with said bar. Furthermore, when the tube 39 is returned toward normal position by the balanced bar after an engaging vane passes out of co-action with the trip member 46, the flow of mercury in said tube lags again, resulting in maintaining the solenoid 23 energized longer than would otherwise be the case.

Having thus described my invention, what I claim as new and desire to secure by Letters Patent of the United States is:

1. In apparatus of the class described, in combination, fuel feeding means, actuating means therefor, coupling means normally interconnecting said fuel feeding means and said actuating means, disconnect means cooperable with said coupling means for uncoupling the same, and means for initiating action of said disconnect means comprising a timing gear operable by said actuating means in timed relation thereto, said gear including elements graduated in respect to their axial lengths, and trip instrumentalities axially adjustable respecting said gear to engage pre-selected ones of said elements.

2. In apparatus of the class described, in combination, fuel feeding means, actuating means therefor, coupling means normally interconnecting said fuel feeding means and said actuating means, and comprising cooperating latches, disconnect means comprising a member cooperable with one of said latches for uncoupling the same, and timing means operable by said actuating means in timed relation thereto and periodically cooperable with said disconnect means for actuating the latter, said disconnect means comprising means for moving said member into the path of said latter latch to disconnect said latches at intervals predetermined by said timing means, said member being movable out of the path of said latter latch by gravity, and said latter latch and said member having cooperating means for maintaining their engagement for a pre-determined period.

3. In apparatus of the class described, in combination, fuel feeding means, actuating means therefor, coupling means normally interconnecting said fuel feeding means and said actuating means, and comprising cooperating latches, disconnect means comprising a solenoid, a member movable into the path of movement of one of said latches for uncoupling the same upon energizing of said solenoid, said member being movable to a position out of cooperation with said latter latch upon de-energizing of said solenoid, means for energizing said solenoid at pre-determined intervals, and means for maintaining cooperative relation of said latch and said member for a pre-determined period after said solenoid is de-energized.

4. In apparatus of the class described, in combination, fuel feeding means comprising a ram, crank means for reciprocating said ram, means for connecting and disconnecting the ram and the crank, and timing means for said latter means comprising trip instrumentalities, a member operable by said crank and trip engaging elements on said member for engaging said instrumentalities and spaced at intervals corre-

sponding with the time of a complete revolution of said crank.

5. In apparatus of the class described, in combination, fuel feeding means comprising a ram, 5 crank means for reciprocating said ram, means for connecting and disconnecting the ram and the crank, and timing means for said latter means comprising trip instrumentalities, a pinion on said crank, a timing gear meshing therewith, and 10 having trip engaging elements thereon spaced at intervals corresponding with the arc of movement of said gear during a complete revolution of said pinion.

6. In apparatus of the class described, in combination, fuel feeding means comprising a ram, crank means for reciprocating said ram, means normally inter-connecting said ram and said crank, and comprising a pitman connected to the ram, a member slidable on said pitman and connected to said crank, a latch on said member, a second latch pivoted to the pitman and engageable with the first latch, and disconnect means movable into and out of the path of movement of said second latch for engagement therewith to disconnect the ram from the crank.

7. In apparatus of the class described, in combination, fuel feeding means comprising a ram, crank means for reciprocating said ram, means normally inter-connecting said fuel feeding means and said crank means and comprising a pitman connected to the ram, a member slidable on said pitman and connected to said crank, a latch on said member, a second latch pivoted to the pitman and engageable with the first latch, 30 disconnect means movable into and out of the path of movement of said second latch for engagement therewith to disconnect the ram from the crank, and timing means operable by said crank means in timed relation thereto, and periodically cooperable with said disconnect means for causing engagement of the latter with said second latch at a pre-determined point in the movement of the pitman.

8. In apparatus of the class described, in combination, fuel feeding means comprising a ram, crank means for reciprocating said ram, coupling means normally inter-connecting said ram and said crank, and disconnect means movable into and out of the path of movement of said coupling means for engagement therewith to disconnect the ram from the crank, and means for maintaining engagement of said disconnect means and said coupling means during a pre-determined degree of movement of the crank.

55 9. In apparatus of the class described, in combination, fuel feeding means comprising a ram, crank means for reciprocating said ram, means normally inter-connecting said ram and said crank, and comprising a pitman connected to the ram, a member slidable on said pitman and connected to said crank, a latch on said member, a second latch pivoted to the pitman and engageable with the first latch, disconnect means movable into and out of the path of movement of said second latch for engagement therewith to disconnect the ram from the crank, and means for maintaining engagement of said disconnect means and said second latch during a pre-determined degree of movement of said pitman.

10. In apparatus of the class described, in combination, fuel feeding means comprising a ram, crank means for reciprocating said ram, means for connecting and disconnecting the ram and the crank, and timing means for said latter means comprising trip instrumentalities, a mem-

ber operable by said crank and trip engaging elements on said member for engaging said instrumentalities and spaced at intervals corresponding with the time of a complete revolution of said crank, said elements each being of a different effective length, and control means for said timing means operable to position the trip instrumentalities for engagement with any desired number of said elements.

11. In apparatus of the class described, in combination, fuel feeding means, actuating means therefor including a crank, means for connecting and disconnecting the fuel feeding means and the actuating means, and timing means operable by said crank to move a pre-determined degree during a corresponding movement of said crank, said timing means including parts spaced at intervals corresponding with said degree of movement, and trip instrumentalities cooperable with

5 said parts for causing disconnection of the fuel feeding means and the actuating means.

12. In apparatus of the class described, in combination, fuel feeding means, actuating means therefor including a crank, coupling means normally interconnecting said fuel feeding means and said crank, disconnect means cooperable with said coupling means for uncoupling the fuel feeding means from the crank during pre-determined cycles of said crank, timing means operable by said crank in timed relation thereto and periodically cooperable with said disconnect means for actuating the latter, and control means cooperable with said timing means for selecting the number of cycles of said crank during which said disconnect means shall be actuated in a given period.

WALTER J. HAAG.
